UNITED STATES PATENT OFFICE

105,458

DESIGN FOR A COMBINED POWER UNIT HOUSING AND MEAT CHOPPER

David A. Meeker, Troy, Ohio, assignor to The
Hobart Manufacturing Company, Troy, Ohio,
a corporation of Ohio

Application February 13, 1935, Serial No. 55,395

Term of patent 14 years

To all whom it may concern:

Be it known that I, David A. Meeker, a citizen of the United States of America, residing at Troy, in the county of Miami, State of Ohio, have invented a new, original, and ornamental Design for a Combined Power Unit Housing and Meat Chopper, of which the following is a specification, reference being had to the accompanying drawing, forming a part thereof and which discloses the preferred embodiment, illustrated as comprising a power unit housing and a meat chopper unit combined therewith, and in which

Fig. 1 is a perspective view of the power unit housing with the meat chopper unit removed;

Fig. 2 is a side elevational view of the power unit housing with the meat chopper unit indicated in dotted lines;

Fig. 3 is a perspective view of the combined power unit housing and meat chopper unit;

Fig. 4 is an end elevational view of the combined power unit housing and meat chopper unit viewed from the right hand end thereof; and

Fig. 5 is an end elevational view of the combined units of Fig. 2 viewed from the opposite direction.

Fig. 1 is lined to show contrasting colors. The dominant feature of the design is the power unit housing which has generally flat side portions merging into a generally curved top portion with the ends connected to the sides and top by beveled portions.

I claim:

The ornamental design for a combined power unit housing and meat chopper substantially as shown and described.

DAVID A. MEEKER.
